UNITED STATES PATENT OFFICE.

ERICH SCHMIDT AND ADOLPH FREDERICK SCHNEIDER, OF NEW YORK, N. Y.

COIN-OPERATED LOCK FOR VEHICLE-WHEELS.

SPECIFICATION forming part of Letters Patent No. 605,749, dated June 14, 1898.

Application filed April 12, 1897. Serial No. 631,719. (No model.)

To all whom it may concern:

Be it known that we, ERICH SCHMIDT and ADOLPH FREDERICK SCHNEIDER, of New York city, in the county and State of New York, have invented a new and Improved Coin-Operated Lock for Vehicle-Wheels, of which the following is a full, clear, and exact description.

The object of our invention is to provide a device whereby a vehicle-wheel may be locked to a predetermined support and, furthermore, to so construct the device that a key-operated lock will be employed in connection with a gate, the key of the lock being capable of withdrawal from the lock only after the bolt of said lock is in locking engagement with the said gate.

Another object of the invention is to provide a means whereby when the gate is freed from the bolt of the lock the key cannot be withdrawn from said lock and whereby, further, the bolt of the lock cannot be carried to locking engagement with the gate until a coin of a predetermined value has been placed in the device.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a perspective view of the improved device. Fig. 2 is a vertical section taken substantially on the line 2 2 of Fig. 3. Fig. 3 is a vertical section taken through the coin-chute and the locking device for the key, the section being taken substantially on the line 3 3 of Fig. 2; and Fig. 4 is a detail view of the slide operating the coin and the parts between which it operates.

A box A is adapted for attachment to any approved support, and in connection with the box a wheel-holder B is employed, which we prefer to construct as shown in the accompanying drawings, in which the wheel-holder consists of a body 10, made from a casting or a forging substantially U-shaped in cross-section, being provided at its front or open vertical portion with a hinged gate 11. The body 10 of the wheel-holder is secured to a

side of the box A in any suitable or approved manner.

Within the box A a coin-chute 12 is located, the coin being introduced into the chute 55 through the medium of a slot 12^a. The coin-chute at its inner side or face is provided with a vertical slot 13 at its bottom portion, and the said coin-chute is open at the top and at the bottom, and the side in which the opening 13 is produced is inclined from the top downward in direction of a side of the box. An arm 14 is pivoted in the opening 13, the arm being of angular construction, comprising a weighted head 15 and a foot 16, the 65 weighted head normally forcing the foot in direction of the side of the casing to which the chute is attached. A plunger-slide 17 has vertical movement in the casing, preferably between the outer wall 19 of the coin-chute 70 and a fixed block 18, secured to the casing, as shown in Figs. 3 and 4, the said block at its lower end being provided with a vertical slot 21, enabling the foot 16 of the arm 14 to engage with the side face of the casing. A 75 spring 22 is secured to the outer wall 19 of the coin-chute near its top and to a pin secured upon the lower portion of the plunger-slide 17 above the central portion of a segmental recess 13^a, which is made in the lower portion 80 of the slide and connects with a vertical slot 13^b. The open top of the coin-chute 12 is secured to the top of the casing A.

A lock-lever 23 is pivoted on the same side of the casing to which the coin-chute is attached below the said coin-chute, the pivot-point 23^a of said lock-lever being at or near its center. At one end of the lock-lever in its upper face a concavity 24 is made, and at the side of the concavity that faces the casing a 90 vertical wall 25 is provided, while at the opposite or inner end of the lock-lever 23 a head 26 is produced, adapted when the lock-lever is in its normal position to engage with a key 27, belonging to a lock 28 of any suitable or approved pattern, the lock-lever in its normal position preventing the key 27 from being turned. The bolt 28^a of the lock extends out through that side of the casing at which the wheel-holder B is attached, and when the bolt 100 is thrown out it will engage with the gate 11 and hold said gate closed. Pillars 29 are illus-

trated as attaching the lock 28 to the casing, and a spring 30 is shown as attached at one end of the casing and coiled around one of the pillars, the free end of the spring having 5 bearing against the under surface of the recessed portion of the lock-lever, holding the lock-lever in horizontal position.

In operation when a key is placed in the lock, as shown in positive lines in Figs. 2 and 10 3, the head of the lock-lever will prevent the key from being turned, and the bolt of the lock will at that time be withdrawn or be mainly within the casing, and as the key cannot be turned when a Yale lock is employed 15 in connection with the device the key cannot be brought to such position at this time as to enable it to be removed. When, however, a coin—a penny, for example—is dropped into the coin-chute 12, it will fall down upon the 20 recessed portion 24 of the lock-lever, engaging with the back wall 25 thereof, and be engaged by the foot 16 of the arm 14, which is both a retaining and an ejecting arm. The coin being in the position just described, by 25 pressing downward upon the plunger-slide the coin will be forced downward by reason of the segmental bottom surface 13^a of the slide engaging with the upper peripheral portion of the coin. As the coin is pressed downward it places the spring 30 under tension and raises the head 26 out of the path of the key 27, permitting said key to be turned to throw the bolt and lock the gate 11 across the rim of the bicycle-wheel, the rim and tire of which 30 are contained in the body 10 of the wheel-holder. The key at this time may be withdrawn. When it is desired to remove the bicycle from the holder, the key is introduced into the lock and turned to throw the bolt inward, whereupon the lock-lever 23 will be 35 raised at its head 26, and after the key has passed the head, which will be when the bolt is entirely withdrawn, the head of the lock-lever will so engage with the key, as shown in Fig. 2, as to prevent the key from being turned or withdrawn, as heretofore stated, unless the necessary coin is placed in the coin-chute and the plunger-slide properly manipulated.

40 50 This device is exceedingly simple. It is durable and its economic and insures the proprietor of a bicycle-stand being properly remunerated for the storage of the wheels. When the plunger forces the coin downward, 55 as shown in dotted lines in Fig. 2, and raises the head of the lock-lever, permitting the key to be turned, the foot 16 of the arm 14 will drop behind the coin, and the moment that the key is withdrawn from the lock after the 60 bolt has been thrown to locking position the spring 30 will restore the lock-lever to its normal position and the coin traveling up the foot-surface of the arm 14, which surface is inclined, will be forced out from the recess 65 24 and will drop into the bottom portion of the box.

Having thus described our invention, we

claim as new and desire to secure by Letters Patent—

1. A lock for a bicycle-wheel, comprising a 70 socket, a gate therefor, a bolt for engagement with said gate, and a coin-controlled means for locking the key of the lock, substantially as described.

2. A casing, a keeper adapted to receive a 75 vehicle-wheel, a bolt adapted for engagement with the keeper and carried by the casing, and a coin-controlled lock-lever adapted to engage the key and prevent its turning or withdrawal, substantially as described. 80

3. A casing, a keeper for a vehicle-wheel, provided with a gate, a lock carried by the casing, the bolt of which is adapted for engagement with the gate of the wheel-keeper, a coin-receptacle, a lock-lever preventing the 85 withdrawal of the key from the lock, said lever being adapted to receive the coin from the said receptacle, and a plunger arranged to move the coin in a direction to raise the lock-lever from the key, as and for the purpose set forth. 90

4. The combination, with a casing, a keeper for a vehicle-wheel, and a gate for the said keeper, of a lock contained in the casing, the bolt whereof is adapted for engagement with the said gate, a lock-lever normally engaging with the key of the lock and preventing its movement, and a plunger operating upon the said lock-lever through the medium of a coin, to raise the lever from the path of the key, as 95 and for the purpose set forth.

5. The combination, with a casing, a keeper adapted to receive the tire and rim of a bicycle-wheel, a gate for the said keeper, and a key-operated lock located in the casing, the bolt 105 whereof is adapted for engagement with the gate of said keeper, of a coin-chute, a lock-lever pivoted below the coin-chute, having a recess to receive a coin and a head which is normally in the path of the key of the lock, 110 a weighted arm arranged for engagement with one face of the said coin, and a plunger adapted to act upon a coin when seated upon the lock-lever, as and for the purpose set forth. 115

6. The combination, with a casing, a keeper adapted to receive the rim and tire of a bicycle or other wheel, a gate provided for the keeper, and a key-operated lock located in the casing, the bolt whereof is adapted for engagement with said gate, of a lock-lever having a portion thereof normally held in the path of the key, preventing its withdrawal and preventing its turning, said lock-lever being provided with a recess adapted to receive the coin, and a vertical wall at one side 120 of the recess, a gravity-arm, the foot portion whereof is arranged for engagement with the coin carried by the lock-lever, engaging said coin at the face opposite that in contact with the said wall, and a plunger arranged to carry 125 the coin in a direction for lifting the lock-lever out of the path of the key, substantially as shown and described.

7. A lock for bicycle-wheels, a lock-lever

for the key, which lever in its normal position prevents the key from being withdrawn or turned, said lever being operated by a coin acting directly upon it for carrying it out of the path of the key, and a plunger operating on the coin, as and for the purpose specified.

8. The combination with a casing, and a lock therein, of a lever arranged in the casing and adapted to engage the key to prevent its movement or withdrawal, said lever being operated by a coin acting directly upon it for carrying it out of the path of the key, substantially as described.

9. The combination with a casing, and a lock therein, of a pivoted and spring-pressed lever adapted to engage the key of the lock and to be engaged by a coin, a coin - chute

above the said lever, and a plunger in said coin-chute, substantially as described.

10. The combination with a casing and a lock therein, of a coin-chute having one wall slotted, a weighted arm pivoted in the slot of the coin-chute, a plunger in the said chute and a pivoted and spring-pressed lever below the coin-chute and adapted to receive a coin therefrom, said lever being adapted to engage the key of the lock and prevent its movement or withdrawal, substantially as herein shown and described.
